UNITED STATES PATENT OFFICE

HALVOR O. HEM, OF TOLEDO, OHIO, ASSIGNOR TO TOLEDO SCALE MANUFACTURING COMPANY, OF TOLEDO, OHIO, A CORPORATION OF NEW JERSEY

SCALE LEVER

Application filed February 25, 1920. Serial No. 361,252.

This invention relates to means for mounting knife edge pivots, and particularly means for securing such pivots to scale levers. As such levers are now constructed, the knife edge pivots are usually placed in the mold in which the lever is to be cast and are thus fixed in place when the metal of the lever solidifies. In order that the scale may weigh properly the pivots in the scale levers must be placed with great exactness, and the practice of casting the levers with the pivots in place results in the loss of many castings, owing to the pivots having been improperly placed or having shifted in the mold. Furthermore, the pivots warp and lose their temper during the casting process and must be reshaped and re-hardened, which, when the pivots are fixed in the lever, involves grinding and heat treating operations that are difficult to perform, especially if the lever be a heavy one. Where the pivot is thus fixed in place it must be a bar of sufficient cross section to support the weight, and as these bars are of high grade steel their cost is considerable. The practice of inserting the pivots in holes drilled or machined in the lever is also followed to some extent. The inserted pivots must in this case, however, be even heavier than those fixed in place by casting, and the expense due to the use of inserted pivots is therefore very great.

The principal object of this invention is to provide improved means whereby pivots containing a minimum amount of expensive metal may be securely and accurately fixed to a scale lever.

Another object is the provision of means whereby the pivots may be securely fixed to a lever so as to be readily detachable and replaceable.

Other objects and advantages will be apparent from the following description, in which reference is had to the accompanying drawings illustrating preferred embodiments of my invention and wherein similar reference numerals designate similar parts throughout the several views.

In the drawings:—

Figure 1 is a side elevation of a lever equipped with my invention;

Figure 2 is an end elevation of the same; Figure 3 is a perspective view of the knife edge pivot employed;

Figure 4 is a section taken substantially on the line 4—4 of Figure 1;

Figure 5 is a perspective view of the pivot retainer forming an element of my invention;

Figure 6 is a section of a lever equipped with another embodiment of my invention, the section being taken on the line 6—6 of Figure 7;

Figure 7 is a side elevation of a fragment of a lever equipped with the pivot and retainer shown in Figure 6;

Figure 8 is a fragmentary side elevation showing another embodiment of my invention;

Figure 9 is a similar view showing a slight modification of the form illustrated in Figure 8;

Figure 10 is a sectional view taken substantially on the line 10—10 of Figure 9;

Figures 11 and 12 are respectively a fragmentary elevation and vertical section showing a further modification, the section of Figure 12 being taken substantially as indicated on the line 12—12 of Figure 11.

Referring to the drawings in detail, and particularly to Figures 1 to 5, the lever 1 is provided with a tapered bore for each pivot and a groove is machined in the wall of each bore. The pivot retainer 2 shown in Figure 5 is formed with a tapered central portion 3 adapted to fit one of the tapered bores in the lever 1, one of the ends 4 of the pivot retainer being small enough to pass through the bore. One side of the pivot retainer is grooved, as at 5, to receive the pivot 6. The pivot 6 (shown in Figure 3) is of hardened steel and the pivot retainer may be of less expensive material. In order to securely clamp the pivot in place the pivot retainer is split from the bottom of the groove to beyond its longitudinal center by a kerf 7 and provided with bolt holes 8 and 9 to receive clamping bolts 10 and 11.

In assembling the structure the pivot 6 is placed in the groove 5 and the retainer is then inserted in the tapered bore in the lever. The bolts 10 and 11 are passed

through the retainer and tightened up and the retainer is then driven tightly into place, the bolts 10 and 11 being further tightened as required. The pivot 6 lying in registering grooves in the lever and pivot retainer acts as a spline to prevent the retainer from turning in the lever.

For the purpose of providing a thrust bearing for the bearing block (not shown), which 10 the knife edge of the pivot 6 is adapted to engage, notched plates 12 of hardened steel are screwed or otherwise secured to the sides of the lever adjacent the pivots 6.

In Figures 6 and 7 I have shown a second embodiment of my invention. In this embodiment the pivot retainer 2^a has an intermediate tapered portion adapted to fit into a tapered bore in the lever 1^a. Instead of being grooved throughout its length, the 20 pivot retainer is provided with a pair of aligned grooves 5^a extending inwardly from each end. Extending obliquely through the retainer and cutting into the corners of the grooves 5^a are holes adapted to receive 25 notched clamping bolts 10^a and 11^a.

In assembling this form of the device, the retainer 2^a is driven into place and the bolts 10^a and 11^a are placed in the bolt holes with the notches in the bolts registering with the 30 corners of the grooves 5^a. Pivot sections 6^a are then seated in the grooves and the bolts 10^a are tightened up, thus securely 35 clamping the pivot sections in place against the opposite walls of the grooves 5^a. In this embodiment thrust bearings for the bearing block which the knife edges are adapted to engage are formed by inserting pins or 40 blocks of hardened steel in depressions in the lever 1^a. The blocks 12^a may be driven into the lever or threaded and screwed into 45 it or they may be merely snugly inserted and held in place by the pivot sections 6^a, as shown in Figures 6 and 7.

In the embodiment shown in Figure 8 the 50 pivot retainer 2^b is substantially like that shown in Figure 5. The knife edge pivot is in two sections 6^b, like those shown in Figure 6, and the thrust bearing consists of a hardened bar rectangular in cross section, 55 which lies in a groove milled in the wall of the bore through the lever 1^b.

In the embodiment shown in Figures 9 and 60 10 the pivot retainer 2^c is substantially like the retainer 2 shown in Figure 1. The pivot 65 is in two sections 6^c. A spline 12^c, of substantially the same width as the pivot sections 6^c, is inserted in the groove 5^c, and when the pivot retainer is inserted into the 70 tapered bore in the lever 1^c the spline 12^c lies 75 in a groove which is milled in the wall of the tapered bore. The pivot sections are seated in the ends of the groove 5^c, the 80 bolts 10^c and 11^c tightened up, and the pivot retainer driven home.

65 In the embodiment shown in Figures 11

and 12 the construction of the pivot retainer 2^d and the lever 1^d is identical with that shown in Figures 9 and 10. The pivot 6^d is like that shown in Figures 1 to 4; the thrust bearing is formed by inserting a grooved bar 12^d in the groove through the lever 1^d; and the groove in the bar 12^d is shaped so as to fit over the central part of the knife edge pivot.

70 From the above description it is apparent that while the pivots 6 sustain the wear, the shearing and bending strains are sustained by the pivot retainers. The pivots may therefore be made of ample strength with the use of very little expensive metal. It is also apparent that the pivots may be removed for re-sharpening or replacement without removing the scale levers.

75 While it will be apparent that the illustrated embodiments of my invention herein disclosed are well calculated to adequately fulfill the objects primarily stated, it is to be understood that the invention is susceptible to variation, modification and change within the spirit and scope of the subjoined 80 claims.

85 Having described my invention, I claim:

1. In a device of the class described, in combination, a lever having a bore therein, a pivot retainer inserted in said bore, said pivot retainer having a groove along one side thereof and a kerf along the bottom of 90 said groove, and a knife edge pivot seated in said groove.

2. In a device of the class described, in combination, a lever having a grooved bore therethrough, a grooved pivot retainer inserted in said bore, a spline in the groove of 95 said bore and said pivot retainer, and a pivot seated in the groove of said pivot retainer.

100 3. In a device of the class described, in combination, a lever having a bore therethrough, a grooved pivot retainer inserted in said bore, there being a kerf in said pivot retainer opening into the groove thereof, a knife edge pivot seated in the groove of said pivot retainer, and clamping means extending 110 transversely of said kerf.

115 4. In a device of the class described, in combination, a lever having a grooved bore therethrough, a grooved pivot retainer inserted in said bore, there being a kerf in said pivot retainer opening into the groove thereof, a spline in the groove of said bore and said pivot retainer, a knife edge pivot seated in 120 the groove of said pivot retainer, and clamping means extending transversely of said kerf.

125 5. In a device of the class described, in combination, a lever having a bore therethrough and a recess above the said bore, a pivot retainer in said bore, pivots mounted on said pivot retainer, and thrust bearing means mounted in said recess.

HALVOR O. HEM. 130
